UNITED STATES PATENT OFFICE

163,627

BEDSIDE STAND

Anthony Paterniti, Jamestown, N. Y.

Application January 8, 1948, Serial No. 143,593

Term of patent 3½ years

(Cl. D5—2)

To all whom it may concern:

Be it known that I, Anthony Paterniti, a citizen of the United States, residing at Jamestown, in the county of Chautauqua and State of New York, have invented a new, original, and ornamental Design for a Bedside Stand, of which the following is a specification, reference being had to the accompanying drawing, forming part thereof; and in which:

Fig. 1 is a side perspective view of a bedside stand showing my new design; and

Fig. 2 is a front perspective view thereof.

I claim:

The ornamental design for a bedside stand, substantially as shown.

ANTHONY PATERNITI.
